UNITED STATES PATENT OFFICE.

JOSHUA POOL AND JOSEPH POOL, OF GREENSBURG, INDIANA.

DESIGN FOR MONUMENTS.

Specification forming part of Design No. **11,450**, dated October 7, 1879; application filed September 9, 1879.
[Term of patent 7 years.]

To all whom it may concern:

Be it known that we, JOSHUA POOL and JOSEPH POOL, of Greensburg, in the county of Decatur and State of Indiana, have originated and designed a new Arched Monument, of which the following is a full, clear, and exact description, reference being had to the accompanying drawing, making part of this specification.

In illustrating and describing this design several devices are shown and described which are secured to us in our Design Patent No. 11,364, granted August 26, 1879, to which we now make no broad claim.

The nature of our design is fully represented in the accompanying drawing, which illustrates an arched monument composed of square and octagonal work, consisting of an oblong base, E, of one or more pieces, the two dies A A', which are square, with octagonal moldings G G' at their tops, the two pillars B B', which are octagonal, the two caps F F', finished with octagonal moldings on their lower sides to match the pillars, and square at their upper sides, as at K K', to match the square ends of the arch C. The arch C may be surmounted by an urn, D, or any other appropriate device.

It is obvious that the moldings G G' F F' may be simple or elaborate, and may be formed by curved or straight lines, as desired, without departing from the essence of our design.

What we claim is—

1. The design of an arched monument, consisting of a combination of square and octagonal work, as fully described above, and shown in the accompanying drawing.

2. The design for an arched monument, consisting of the base E, of one or more pieces, the two dies A A', which are square, with octagon moldings G G' at their tops, the two octagonal pillars B B', the two caps F F', finished with octagonal moldings on the lower sides to match the pillars, and square at their upper ends, as at K K', to match the square ends of the arch C, substantially as described, and shown in the accompanying drawing.

In testimony whereof we have signed our names to this specification in the presence of two subscribing witnesses.

JOSHUA POOL.
JOSEPH POOL.
